(57) **CLAIM**

The ornamental design for a specimen container as shown and described.

DESCRIPTION

FIG. 1 is a front right top perspective view of a specimen container showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear right bottom perspective view thereof;

FIG. 9 is a cross-sectional view taken in the direction of line 9-9 in FIG. 6; and,

FIG. 10 is a partial enlarged view of the circled region 10 in FIG. 6.

The dashed broken lines depict portions of the specimen container that form no part of the claimed design.

The dot-dash broken line in FIG. 9 is for defining the bounds of the claimed design only and forms no part of the claimed design.

The dot-dash broken line indicia in FIGS. 6 and 10 are included for the purpose of disclosing the cross-sectional and partial enlarged views, and form no part of the claimed design.
